ATTORNEY

UNITED STATES PATENT OFFICE

HANS SYVER BERG, OF VENTURA, CALIFORNIA

AUTOMATIC FLOW NIPPLE AND SEPARATOR FOR OIL WELLS

Application filed June 11, 1927. Serial No. 198,129.

This invention relates to devices for controlling the flow of water, sand, oil, gas and the like from oil wells.

One object is to provide a device of such character which will respond to pressure fluctuations in the flowing stream and will be automatic in its operation. Another object is to enable adjustment whereby the range of automatic operation may be varied in the event that such adjustment is required to care for great changes in pressure or for change in the character of the flowing material, as for example when a flow of water and sand or mud is finally replaced by a flow of oil or oil and gas. And a still further object is to associate with the nipple a means for accomplishing at least a rough separation of water and solids from the oil.

Briefly stated, the invention resides in a flow nipple, or as it is frequently called a "flow bean," which comprises a chamber having an inlet and automatic valve controlling said inlet. The valve is movable by the pressure of the incoming stream and against the influence of some yielding tensioning means such as a spring. The upper one of a pair of outlets from the chamber is controlled by a second valve which may cooperate with a Venturi tube and may conveniently be carried on the stem of the first valve. Means for adjusting the tension may also be provided. The valves yield as the pressure increases. Water and sand or mud may be allowed to separate out in the chamber and leave by the lower outlet while the oil passes out through the venturi around the second valve. When the flow settles down to clean oil the discharge from said outlets may be governed by gate valves therebeyond. The invention also resides in such other features of novelty as may be herein set forth.

In the accompanying drawings wherein one embodiment of the invention is disclosed by way of illustration,

Fig. 1 is an elevation showing the location of two of the present structures in the flow connections from an oil well.

Fig. 2 is a vertical section through one of the nipples.

Fig. 3 is a cross section therethrough taken on the line 3—3 of Fig. 2.

These drawings show the usual outer casing 10 with the casing head 12 and the flow tube 14 to which is attached the cross fitting 15 from which lead the connections 16 containing gate valves 17, together with the T-fittings 18, bull plugs 19, and other parts of the typical arrangement commonly referred to as the "Christmas tree."

From each of the T-fittings 18 there rises a short connection 20 upon which there is mounted the casing 22 of the receiving chamber which carries the present invention. At one end of this chamber an outlet is provided from which a discharge connection 24 leads to a T 25 connected with a discharge line 26 containing a gate valve 27. Between the T 25 and another T 28 there is provided another gate valve 29 whereby oil may be transferred from connection 24 to a discharge line 30 which also receives oil from a connection 31 which in turn receives from an upper chamber contained in a housing 32 smaller than the receiving chamber and mounted thereupon through the medium of a Venturi tube 33 threaded into a collar which is bolted to the top of the casing 22 and provides an upper outlet therefrom.

The inlet of the casing 22 is provided with a tapered seat 35 cooperating with a cone valve 36 carried on the lower end of a stem 37 which passes upward through the lower conical portion 38 of the Venturi bore and is joined at 39 to the lower end of a sleeve or socket 40 whose lower portion is in the form of a tapered valve 41 cooperating with the upper conical portion 42 of the Venturi bore. Within the socket 40 there is disposed a spring 44 engaged by the lower end of an adjusting spindle 45 which passes up through the housing 32 and through a packing gland 46 in a block 48 bolted to the housing and carrying a bracket 49 which supports an adjusting wheel 50 for the spindle 45. The lower end of the spindle serves as a guide for the valve 41 while the lower valve 36 is guided by a series of pins 52 depending from a ring 54 threaded into the casing 22 at the upper

outlet and engaging in grooves 55 within the rim of said valve 36.

In operation, the incoming flow of water, mud or oil or mixture thereof lifts the valve 36 in proportion to the pressure of the stream and the tension of the spring 44, the latter being adjusted as desired by the hand wheel 50. The capacity of the chamber 22 is sufficient to permit at least a fair separation of water, sand and mud from the oil, the water and heavier materials then flowing out through the connection 24 and being discharged through the line 26 past the gate valve 27, the valve 29 being closed. The oil 10 rises above the water and passes up through the Venturi bore 38, 42 around the valve 41, and by way of the chamber 32 to the connection 31 and discharge line 30. The venturi has considerable value since it permits an 15 easy flow of the oil and reduces turbulence, thereby in turn reducing the formation of emulsions with any small amounts of water which may be carried over with the oil. When the flow clears up and only oil and gas 20 come through, the valve 27 will be closed, the tension of the spring 44 adjusted if necessary, and preferably the valve 29 will be opened so that the bulk of the flow may be through said valve 29. In any event, the tension of the 25 spring and the weight of the valve 36 tend to regulate the flow of liquid, the flow inlet being reduced as the pressure drops and increased as the pressure rises, whereby the flow is properly controlled as the conditions vary.

35 What I claim is:

1. In a flow nipple, a receiving chamber having an inlet, a lower outlet and an upper outlet, a second chamber connected with said upper outlet and receiving therefrom, a Venturi tube forming said connection, and connected tensioned valves for said inlet and said Venturi tube to control the flow into the respective chambers.

2. A flow nipple comprising a receiving chamber having an inlet, an upper outlet and a lower outlet, said chamber being adapted to permit the separation of oil and water therein whereby water may flow from the lower outlet and oil from the upper outlet, an automatically operating valve for controlling said inlet, an automatically operating valve for controlling the upper outlet, and tensioning means for said valves whereby the valves open as the pressure of the incoming stream increases.

3. A flow nipple comprising a receiving chamber having an inlet, a lower outlet and an upper outlet, a second chamber carried above the receiving chamber and having an 60 inlet connected with said upper outlet, a valve in said receiving chamber controlling the inlet thereto, a stem for said valve projecting into the inlet to the second chamber, a valve mounted on said stem and controlling the 65 said inlet, and means for tensioning said

valves to urge them toward the respective inlet to control flow therethrough.

4. A flow nipple for oil wells comprising a receiving chamber having an inlet, an upper outlet and a lower outlet, said chamber being 70 adapted to permit the separation of fluids of different specific gravities therein, whereby fluid of one specific gravity may flow from the lower outlet and fluid of a different specific gravity from the upper outlet, an automatically 75 operating valve for controlling said inlet, an automatically operating valve for controlling the upper outlet, and tensioning means for said valves, whereby the valves open as the pressure of the incoming fluid 80 stream increases.

In witness that I claim the foregoing I have hereunto subscribed my name this 18th day of May, 1927.
